COMBINED TELEVISION STAND AND SHELF

Walter Gusdorf, Brentwood, Mo.

Application July 27, 1959, Serial No. 56,950

Term of patent 3½ years

(Cl. D33—14)

Fig. 1 is a perspective view from the front of a combined television stand and shelf showing my new design;

Fig. 2 is a perspective view of the television stand and shelf of Fig. 1 showing the opposite end thereof; and

Fig. 3 is a perspective view from the end of the television stand and shelf looking downwardly thereon.

I claim:

The ornamental design for a combined television stand and shelf, substantially as shown.
